UNITED STATES PATENT OFFICE

JAMES McRAE, OF BROOKLYN, NEW YORK, ASSIGNOR OF ONE-HALF TO JOHN LANGENHOP, OF MASPETH, LONG ISLAND, NEW YORK

EQUALIZING DEVICE

Application filed May 2, 1928. Serial No. 274,585.

This invention relates to equalizing devices, an object of the invention being to provide a measuring instrument including a plurality of pins manually movable so as to simultaneously move all of the pins, varying the distance between the pins but maintaining all of the pins spaced equally. In other words, my improved device includes pins or analogous pointers or indicators or puncturing devices which are spaced apart and which are moved simultaneously by a manually movable member to vary the distance between the pins but to maintain all of the pins equally spaced.

With a device of this kind the pins may be spaced apart any desired distance and all of the pins will function to mark or indicate points as, for example, in calibrating or dividing, a plurality of indicators or markers are provided for simultaneous use.

With a device of this character any given space may be divided into aliquots, and the instrument may be adapted for any use where such a device is desirable.

Furthermore, my improved device is of extremely simple construction and embodies few parts so that it may be manufactured and sold at a reasonably low price and most efficiently perform the functions for which it is intended.

With these and other objects in view, the invention consists in certain novel features of construction and combinations and arrangements of parts, which will be more fully hereinafter described and pointed out in the claim.

In the accompanying drawings—

Figure 1 is a plan view of my improved device with the cover plate removed;

Figure 2 is a view similar to Figure 1, showing the pins at a different adjustment;

Figure 3 is an enlarged view in transverse section on the line 3—3 of Figure 1 with the cover plate in position;

Figure 4 is a perspective view of one of the indicator or marker pins.

1 represents a body, which may constitute a strip of any suitable material having its face recessed, as shown at 2, to accommodate a series of pins 3 and also having a segmen-

tally shaped recess 4 with which a longitudinal recess 5 communicates. A cover plate 6 may be secured on the body 1 so as to confine all the mechanism, which will now be explained.

In the segmental recess 4 an arm 7 is mounted to move and is pivotally connected to the body at one end of the arm, as shown at 8. This arm 7 has a longitudinal slot 9 therein and is engaged by a sliding bar 10 which may have a pin 11 engaging in the slot 9 and movable through the recess 5 and having a fingerhold 12 at its outer end to facilitate gripping the same to move the arm 7.

The pins 3 above referred to may constitute wires bent at right angles so that each pin 3 has a portion 13 which extends longitudinally of the device and is provided with a finger 14 engaging in the slot 9 of arm 7. The pins 3 project beyond the edge of the body 1 so that they may be used as indicators or markers, and the longitudinal portions 13 of said pins are of varying lengths so that all of the pins are spaced equally apart.

The operation of the device is as follows:

Figure 1 shows the pins equally spaced and the arm 7 swung to one extreme position. To increase the space or distance between the pins 3, the bar 10 is drawn outwardly, swinging the arm 7 to the right of Figure 1, and the extreme movement of the arm is indicated in Figure 2. The movement of the arm 7 to the right of Figure 1 not only causes all of the pins to move to the right but increases the distance or space between the pins so that by the movement of the arm 7, due to the movement of the bar 10 or through the medium of any other suitable mechanism, all of the pins are moved to vary the distance or space between the pins or markers; and it is this broad idea which constitutes the invention, and I do not wish to be limited to the specific details of construction but desire to cover broadly the idea as expressed.

Various changes and alterations might be made in the general form of the parts described without departing from my invention and hence I do not limit myself to the precise details set forth but consider myself at liberty to make such changes and altera-

tions as fairly fall within the spirit and scope of the appended claim.

I claim:

An equalizing device including an elongated support having a segmental recess therein adjacent one end thereof, and a longitudinal recess adjacent the said end of the support communicating with the segmental recess and extending to the end of the support, an arm pivotally connected to the support and adapted to swing in the segmental recess, an operating bar for the manual manipulation of the arm, said bar being pivotally and slidably connected at one end to the arm and movable through the longitudinal recess, a plurality of rods extending longitudinally on the support, pins on said rods projecting transversely beyond a longitudinal edge of the support, and said rods and pivoted arm having slot and pin connection.

Signed at New York in the county of New York and State of New York this 1st day of May, A. D. 1928.

JAMES McRAE.
